UNITED STATES PATENT OFFICE.

BENVENUTO COMBA, OF TURIN, ITALY, ASSIGNOR TO EDWARD CASPER,
OF LONDON, ENGLAND.

RECOVERY OF COPPER FROM SOLUTIONS CONTAINING IT.

No. 820,555.

Specification of Letters Patent.

Patented May 15, 1906.

Application filed September 14, 1903. Serial No. 173,185.

To all whom it may concern:

Be it known that I, BENVENUTO COMBA, a subject of the King of Italy, residing at 40 Via Po, Turin, in the Kingdom of Italy, have 5 invented new and useful Improvements in the Recovery of Copper from Solutions Containing It; and I do hereby declare that the following is a full, clear, and exact description of the invention, which will enable others skilled in the art to which it appertains to 10 make and use the same.

This invention relates to improvements in the process of precipitating copper from acid liquors containing it—for example, a solution of sulfate of copper obtained by lixiviations of roasted copper pyrites or iron pyrites containing copper—and which is effected by the substitution for the copper of another metal of less value, usually scrap-iron.

Now in lieu of immersing the precipitating metal in the cupreous liquor and recovering the copper in the form of an impure sludge containing on analysis from sixty to seventy per cent. of the copper from the solution in 15 an impure state I make use of an apparatus which in principle resembles a large Daniell cell, but without diaphragms, and in which the precipitating metal is separated from the cupreous liquor and is dissolved without 20 coming into contact with the copper, the said copper being precipitated in a pure state electrolytically upon sheets of copper or lead, preferably lead, and in such a ductile condition as to be ready for rolling.

To enable the invention to be fully understood, I will describe it by reference to the accompanying drawings, in which—

Figure 1 is a longitudinal section of suitable apparatus for carrying out the invention. 40 Fig. 2 is a partial transverse section thereof, and Fig. 3 is a partial plan view of the apparatus.

a is a water-tight vat or bath of suitable shape and size and which may be of wood, 45 rubble, or brick, or other suitable material. Near the upper edge of the vessel or bath *a* and above the level of the cupreous liquor are fixed cross-pieces of wood *b b*, supported upon the ledges *c c*, and upon these cross-pieces *b b* are 50 suspended sheets *d d* of lead, (cleaned and then rubbed with powdered graphite,) upon each side of which sheets the copper from the cupreous liquor is to be deposited.

If scrap-iron is used, a sheet *e* of copper

55 gauze is placed upon the upper ends of the metal sheets *d d*, upon which the scrap-iron *f* in any suitable form is placed. This gauze *e* is caused by the weight of the iron *f* to make contact with all the metal sheets *d d*, which are thus all placed in electric connection, so 60 that they all remain in the same electrical condition during the operation of the apparatus. This gauze sheet, however, is only necessary when small pieces of old iron—such as nails, &c.—are employed. If pig-iron or 65 old rails or bars or large pieces of iron which can rest upon two or three adjacent vertical sheets are employed, the said gauze is not necessary.

The iron and lead electrodes being arranged in the vat or bath *a*, as above described, slightly acidulated warm water is introduced to a slight depth in the bottom of the bath, after which the cold cupreous liquor is gently admitted, this being effected 70 through a feed-tube *g*, which is inserted into a wide tube *h*, extending to the bottom of the bath, with which it communicates by the holes *h' h'*, the feed-tube *g* reaching nearly 75 to the level of these holes, so that the liquor is relieved of any air which it may contain 80 before entering the bath. The liquor in rising up the bath *a* raises the warm water on account of the difference in their specific 85 gravities, and when this warm acidulated water comes into contact with the iron scrap or the like *f* the electrolytic action commences. The plane separating the acidulated 90 water and the liquor will be observed to gradually drop as the liquor deposits its copper upon the vertical lead sheets and 95 loses its color. Fresh liquor will then be automatically introduced below, as above described, and the operation can be regulated 100 with facility in such a manner that the cupreous liquor is never allowed to come into contact with the upper precipitating metal. The spent liquor which is gradually raised overflows at *i* and can be conveyed away for reuse and crystallization.

j is a pipe running around the vat *a* at the upper part above the gauze *e* and through which steam is caused to circulate for the purpose of maintaining the temperature of the acidulated water at the requisite degree 105 for efficient operation.

The level of the cupreous solution is always a few centimeters below the contact be-

tween the iron and the heads of the copper plates forming the electrodes. The copper is precipitated in greater quantity at the upper parts of the plates forming the cathodes—that is to say, in the vicinity of the contact between the two liquids—since the current immediately on its generation is more intense and has less resistance offered to its flow. The precipitated copper diminishes in thickness from the said level downward as the resistance increases with the path which the current must take in flowing from top to bottom of the cathodic plate.

The apparatus shown and described herein is not specifically claimed, as it will form the subject-matter of a separate application for Letters Patent of the United States.

Having now particularly described and ascertained the nature of my said invention and in what manner the same is to be performed, I declare that what I claim is—

1. The method of recovering copper from solutions containing it, which consists in placing the solution in a suitable vessel, immersing a cathode therein, superimposing a liquid of less specific gravity upon the surface of the copper solution, and supporting an anode in said supernatant liquid, in direct contact with the cathode, whereby an electric current is generated and pure copper is deposited upon the cathode, substantially as described.

2. The method of recovering copper from solutions containing it, which consists in placing the solution in a suitable vessel immersing a cathode therein prepared for the

deposition of copper thereon, superimposing an acidulated liquid of less specific gravity than the copper solution, supporting an anode in said supernatant liquid out of contact with the copper solution and in contact with the cathode, supplying additional copper solution adjacent to the bottom of the solution in said receptacle, to maintain the line of separation between the liquids substantially constant and drawing off the excess of supernatant liquid, as the action progresses, substantially as described.

3. The method of recovering copper from solutions containing it, which consists in placing the solution in a suitable vessel, immersing a cathode therein, superimposing a liquid of less specific gravity upon the surface of the copper solution, and supporting an anode in said supernatant liquid and connecting it electrically with the cathode, and applying heat artificially to the supernatant liquid, substantially as described.

4. The method of recovering copper from solutions containing it which consists in placing the copper solution in a suitable receptacle, and immersing therein a cathode adapted to receive a deposition of copper thereon, superimposing acidulated water upon the copper solution and immersing iron in said acidulated water, out of contact with the copper solution and in contact with the cathode, substantially as described.

BENVENUTO COMBA.
